WATER CLOSET FOR BOATS

Edward Hoerichs, Baltimore, Md.

Application March 26, 1937, Serial No. 133,236

3 Claims. (Cl. 4—10)

The present invention relates to water closets, and more especially to those adapted for use on boats; and the primary object is to provide a water closet which may be mounted with the lower 5 end of the bowl or hopper at or immediately below the water-line of the boat but which shall effectively eject its contents automatically and avoid splashing of water upwardly into the bowl without requiring the use of valves, pumps or 10 other objectionable parts.

A more particular object of the invention is to provide means below the bottom of the hull of the boat to receive refuse from the bowl and operative, by the action of the water due to the 15 forward motion of the boat, to effectively withdraw and discharge such refuse, said means also serving to prevent splashing of water upwardly into the bowl due to pitching or rolling of the boat, either while in motion or anchored, said 20 means being self-cleaning while the boat is anchored or not in motion.

Another object is to provide means, operative automatically in consequence of the forward motion of the boat in the water, to force water tip- 25 wardly and discharge it into the upper portion of the bowl for flushing it.

A further object of the invention is to provide a novel and improved mounting for the bowl which is adjustable to enable the bowl to be 30 mounted at different heights above the bottom of the hull of the boat so that the lower end or discharge outlet of the bowl may occupy a pre-determined or desired height with respect to the water-line and to compensate for different angles 35 of transverse and longitudinal inclinations of the bottom of the hull of the boat in order that the bowl may occupy an upright or level position when installed in different boats.

To these and other ends the invention consists in certain improvements and combinations and arrangements of parts all as will be herein- 40 after more fully described, the features of novelty being pointed out more particularly in the claims at the end of this specification.

45 In the accompanying drawing:

Figure 1 is a longitudinal vertical section through a boat having installed therein a water closet in accordance with the present invention;

Figure 2 is a vertical section taken on the line 50 2—2 in Fig. 1;

Figure 3 is a top plan view of the improved stand or mounting for the closet bowl;

Figure 4 is a side elevation of the mounting or stand showing the manner of mounting it on the laterally sloping side of the bottom of the hull of a boat;

Figure 5 is a perspective view of the mounting or stand with its members in adjusted relation substantially as shown in Fig. 4;

Figure 6 is a detail top plan view of the scoop

for receiving and forcing water into the upper portion of the bowl for flushing it; and

Figure 7 is a view similar to Fig. 5 but showing the upper member of the stand adjusted to a higher position.

Similar parts are designated by the same reference characters in the several figures.

Water closets according to the present invention are adapted to be applied to boats of various sizes and types, and the preferred embodiment 10 of the invention is shown in the accompanying drawing and will be hereinafter described in detail. It is to be understood however that the invention is not restricted to the particular construction shown since equivalent constructions 15 are contemplated and such will be included within the scope of the claims.

As shown in the drawing, 1 represents a portion of the bottom of the hull of a boat, the hull bottom sloping longitudinally or in a fore and aft direction as shown for example in Fig. 1 and also sloping laterally or in a direction from the keel to the side of the hull, although it will be understood that the closet is applicable also to boats the bottom of the hull of which is flat or level, either longitudinally or transversely or in both of such directions. 2 represents the closet bowl which may be of any usual or well known construction, it having an annular channel 3 at its top or rim and apertures 4 leading therefrom to the sides of the bowl for flushing it, the lower or discharge end 5 of the bowl being surrounded by an outwardly extending flange 6 which is preferably located above the lower extremity of the bowl.

The closet bowl is mounted on a stand which, 35 according to the present invention, is universally adjustable to compensate for the slope of the hull bottom in a fore and aft direction and a slope of the hull bottom in a direction from the keel to the side of the boat, and is also adjustable so 40 that it may support the bowl at different heights above the water-line of the boat in order that the lower or discharge end of the bowl may occupy the proper height with respect to the water-line. The stand as shown in the present instance comprises upper and lower plates 7 and 8 which may be composed of metal castings, these plates having openings 9 and 10 formed centrally therein and having pairs of segments 11 and 12 cast thereon or otherwise fixed thereto at opposite sides 50 of the central openings in the respective plates, the pair of segments on one plate being closer together than the pair of segments on the other plate so that they may fit between them. Each of the segments 11 on the plate 7 is provided 55 with a series of holes 13 which are preferably spaced equi-distantly, one of these holes being concentric with the arcuate periphery of the respective segment, and each of the segments 12 on the plate 8 is provided with a series of holes 14, 60

these holes being also equi-distantly spaced and one of these holes being concentric with the arcuate periphery of the respective segment. Bolts 15 extend through the holes in the respective segments 11 which are concentric with the arcuate peripheries of these segments and through holes in the segments 12 and serve to clamp together the pairs of segments on the plates 7 and 8. Locking bolts 16 are also inserted in appropriate holes 10 in the segments 12, these bolts having washers 17 which overlap the arcuate peripheries of the respective segments 11 and serve as means for firmly clamping the segments 11 and 12 together after they have been adjusted into the appropriate angular relationship.

The lower plate 8 of the stand is adapted to be mounted on the bottom 1 of the hull and to be clamped in water-tight engagement therewith by bolts 18 or other suitable means. A ferrule or pipe 20, composed of lead or other suitable ductile material and of a size to fit over the discharge end of the bowl below the flange 6 thereon is extended through the openings 9 and 10 in the plates 7 and 8 and through an opening 21 of appropriate size formed in the bottom 1 of the hull. The lower end of this ferrule is peened or otherwise flanged outwardly against the underside of the hull bottom 1 and may be secured in water-tight engagement therewith by nails 22. The upper end of the ferrule is peened or otherwise flanged outwardly and is secured, as by nails 23 to the upper side of a board 24 of wood or other suitable material which is placed on the upper side of the plate 7, the board 24 having a central opening 35 therein of sufficient size for the passage of the ferrule. The bowl is firmly secured on the stand by bolts 25 which extend through the flange 6, plate 7 and board 24, these bolts, when tightened, firmly securing the bowl on the top of the stand and clamping the overturned flange on the ferrule and thus forming a water-tight joint between the bowl and the ferrule.

The present invention provides means for automatically withdrawing refuse from the bowl while the boat is in motion, such means comprising a shoe 26 which may be composed of a cast 45 ing the forward end of which is preferably curved and is provided with an aperture 27 and the rear end of which is open, as at 28 for the discharge of the refuse. The shoe is provided at its upper 50 edge, at the front and sides thereof, with an out-turned flange 29 adapted to fit against the under-side of the hull bottom and to be secured in water-tight engagement therewith by screws 30 or other 55 suitable securing means. The interior of the shoe communicates with the lower end of the ferrule 20.

The present invention also provides means for receiving water from the exterior of the boat while the latter is in motion and for forcing the water upwardly into the flushing channel 2 in the upper portion of the bowl, such means comprising a scoop 31, which may be composed of a hollow casting having a surrounding flange 32 adapted to fit against the underside of the hull bottom and to be secured in water-tight engagement therewith by screws 33 or other suitable means. The forward side of the scoop or the side thereof which faces the bow of the boat is provided with a suitable number of slots 34 to admit water thereto incident to the forward motion of the boat, and the rear portion of the scoop is formed at the top with a plate 35 into which a pipe 36 is threaded, this pipe being connected at its upper end to the flushing channel 3 in the

bowl and being extended downwardly through the bottom of the hull into the plate 35, a lock nut 37 being preferably threaded on the pipe 36 to secure the latter to the scoop and form a water-tight joint around the lower end of the pipe.

In installing the closet in a boat, the stand may be mounted with the lower plate 8 resting on the hull bottom and inclined to conform with the incline or inclines of the hull bottom, and the upper plate 7 set in a level position, the bolts 15 connecting the segments 11 and 12 permitting such relative angular adjustment of the plates and the bolts 17 locking the plates in angularly adjusted relationship. The bowl is preferably mounted at such as height with respect to the water-line $x-x$ of the boat as to cause water from the exterior of the boat to normally rise in the lower end of the bowl to a height slightly above the flange 6 thereof as shown in Fig. 1, the mounting of the bowl at the desired height being accomplished by placing the bolts 15 and 17 in the appropriate vertically spaced holes 14 in the segments 12, tightening of these bolts firmly securing the plates 7 and 8 in adjusted relationship. In installing the closet in a boat the bottom of the hull of which slopes upwardly from the keel to the side of the boat, the stand may be mounted on the hull bottom in the manner shown in Fig. 4, the segments 11 and 12 being located at the front and rear sides of the ferrule 20 and the plates 7 and 8 being properly adjusted angularly about the bolts 15 as pivotal centers so that the plate 8 may occupy an inclined position corresponding to the lateral slope of the hull bottom and the upper plate 7 may occupy a level position, and the plates are firmly secured in such angular relationship by tightening of the bolts 15 and 17. In installing the bowl in a boat the bottom of which slopes in a fore and aft direction as well as laterally, the slope of the hull bottom in both of said directions may be compensated for by rotating the stand more or less about its vertical axis from the position shown in Fig. 4 into the position shown for example in Fig. 5 while the lower plate 8 rests on the boat bottom, and rocking the upper plate 7 about the pivot bolts 15 until it assumes a level position, after which the plate 7 is firmly secured in such position by tightening of the bolts 15 and 17. In installing the bowl under any of these conditions, the ferrule 20 is inserted after the upper and lower plates of the stand have been adjusted with respect to the height of the bowl above the hull bottom and the slope or slopes of the hull bottom, the ductile material of which ferrule is composed, as for example of lead, enabling it to be shaped at its upper end to conform with the level position of the bowl and at its lower end to conform with the slope or slopes of the hull bottom, and also permitting it to be peened or flanged as hereinbefore described.

In those installations where it is desirable or necessary to place the bowl in a higher position above the bottom of the hull, the stand may be 65 adjusted in the manner shown in Fig. 7. In this figure, the upper member or plate 7 is set higher above the bottom member or plate 8 than in Fig. 5, and the bolts 15 are placed in holes 13 in the segments 11 which are adjacent to the lower 70 edges thereof and in the upper holes 14 in the segments 12, and bolts 16^a are placed in appropriate holes 13 in the segments 11 immediately above the upper curved edges of the segments 12, these bolts having peripherally toothed 75

or serrated washers 16^b thereon which are eccentric to the respective bolts 16^a and are adapted to grip or mesh with the correspondingly toothed or serrated curved edges 12^a on the segments

5 12. In using this arrangement, the upper and lower plates 7 and 8, after being adjusted to the desired height and set in the proper angular relation to bring the upper plate 7 level and compensate for slope of the bottom of the hull in a 10 fore and aft and/or a lateral direction, are securely locked by rotating the eccentric washers in opposite directions on the respective bolts 16^a until these washers engage the respective serrated edges of the segments 12, the longest radii 15 of the eccentric washers then extending divergently toward opposite sides of the axes of the bolts 16^a, and then tightening the bolts 16^a and the bolts 15, the divergent setting of the eccentric washers causing them to lock against the 20 segments 12 and to firmly prevent rocking of the upper plate 7 in either direction relatively to the lower plate 8. The stand as thus adjusted, may be otherwise installed and used in the same manner as hereinbefore described.

25 13. In operation, water from the exterior of the boat will normally rise into the lower end of the bowl to the level of the water-line x—x, or substantially so. Any refuse that may be contained in the lower end of the bowl or in the 30 ferrule, while the boat is at anchor or not in motion, will be withdrawn and washed out of the discharge end 28 of the shoe 26 by water entering the shoe through the aperture 27 incident to the tide or current of water beneath 35 the hull. When the boat is in motion in a forward direction, water will enter the slots 34 in the scoop 31 and will be forced by the pressure of the water, incident to the forward motion of the boat, upwardly through the pipe 36 into 40 the channel 3 surrounding the upper end of the bowl and such water will discharge through the openings 4 into the bowl, thereby flushing or washing it. At the same time, the movement of the shoe 26 through the water will produce a 45 partial vacuum at its rear discharge opening 28 which will act to withdraw water and refuse from the lower end of the bowl and ferrule 20 and to eject the same into the water, and also water will enter the aperture 27 in the forward 50 wall of the shoe thereby producing a current rearwardly in the shoe which will assist in ejecting refuse therefrom. Since the shoe 26 covers the lower or discharge end of the ferrule 20, it will serve to prevent splashing of water upwardly 55 into the bowl incident to pitching of the boat in the water.

60 The stand provided by the present invention enables the closet bowl to be readily mounted at the desired height with respect to the water-line of the boat so that the proper amount of water may be normally contained in the lower portion of the bowl to provide a seal, and it enables the bowl to be mounted in a level position irrespective of the fore and aft or transverse slope of the bottom of the boat hull, thus obviating the necessity of cutting a special block for mounting the bowl to suit each installation as heretofore required and which is difficult and laborious.

65 70 The shoe beneath the bowl discharge will effectually withdraw refuse from the lower portion

of the bowl and from the ferrule automatically in consequence of the forward motion of the boat in the water, and at the same time, the scoop will force water from beneath the boat upwardly into the upper portion of the bowl for washing or 5 flushing it. While the boat is anchored or at rest, refuse will be washed automatically from the shoe by the tide or current of the water which will enter the aperture in the front end of the shoe and pass out through the discharge opening 10 in the rear thereof, thereby keeping the shoe clear of refuse. These results are all attained by the present invention without requiring the use of valves, pumps or other accessories which are liable to get out of order and are otherwise objectionable. 15

I claim as my invention:

1. A water closet for boats comprising a bowl having means for mounting it in a boat and having a discharge pipe at its lower end extending 20 directly downwardly therefrom to below the water line of the boat, said discharge pipe being open at its lower end beneath the bottom of the boat hull and providing a body of water in the lower portion of the bowl, and a member adapted 25 for attachment to the under side of the bottom of the hull beneath the open end of the bowl discharge pipe and operative to prevent splash of water into said discharge pipe, said member being open at its rear side and operative by the 30 action of the water thereon during the forward motion of the boat, to withdraw refuse from the bowl.

2. A water closet for boats comprising a bowl having means for mounting it in a boat and having a discharge pipe at its lower end extending directly downwardly therefrom to below the water line of the boat, said discharge pipe being open at its lower end beneath the bottom of the boat hull and providing a body of water in the 40 lower portion of the bowl, and a member adapted for attachment to the under side of the bottom of the hull beneath the lower open end of the bowl discharge pipe and having a wall beneath 45 said open end of the discharge pipe, said member being open at its rear side for the discharge of refuse from the bowl and closed at its opposite side and provided with an aperture located above the level of said wall for admitting and directing 50 a jet of water over the surface of said wall and toward the open side of said member.

3. A water closet for boats comprising a bowl having means for mounting it in a boat and having a discharge pipe at its lower end extending downwardly therefrom to below the water line of 55 the boat and through the bottom of the boat hull and providing a body of water in the lower portion of the bowl, the bowl having flushing means in its upper portion, a member adapted for attachment to the underside of the bottom of the 60 hull beneath the bowl discharge pipe and operative, by the action of water thereon during forward motion of the boat, to withdraw refuse from the bowl, and means adapted for attachment to the underside of the boat hull and connected to 65 the flushing means in the upper portion of the bowl and operative, during forward motion of the boat, to force water into the flushing means to flush the bowl.
